SCAVENGER ROLL MECHANISM

John A. Kooistra, North Andover, Mass., assignor
to Davis & Furber Machine Company, North
Andover, Mass., a corporation of Massachusetts

Application June 4, 1947, Serial No. 752,412

5 Claims. (Cl. 57—34.5)

1

This invention relates to the scavenger roll mechanism of a yarn forming frame, such for example as a spinning frame in which the scavenger rolls are mounted in pairs on individual shafts, one pair for each pair of drawing rolls.

The object of the invention is to provide a simple and efficient means for driving the scavenger rolls.

The object of the invention is further to provide a construction enabling each scavenger roll shaft with its pair of scavenger rolls, independently of the others, readily to be removed and replaced either as required by cleaning, repairing, or substitution.

The object of the invention is further to enable each bearing bracket for each scavenger roll shaft, independently of the others, readily to be removed and replaced.

These and other objects and features of the invention will appear more fully from the accompanying drawing and description and will be particularly pointed out in the claims.

The invention is applicable to any type of yarn forming frame for twisting, spinning, or handling any type of fibrous strand where it is desirable to employ scavenger rolls. Since there are a wide variety of such frames depending upon the particular kind of fiber being processed and the particular stage in the process and since the invention is applicable to any such, it is only necessary to illustrate and describe one example of the parts of one such frame in connection with a disclosure of a preferred form of the present invention. In all such frames there are arranged at spaced intervals sets of horizontally aligned cooperating drawing rolls including for their operation a common horizontal driving shaft. If there is but one such horizontal shaft, it is positively driven, by suitable connections in the frame, and if there are two such shafts extending throughout the aligned cooperating drawing rolls, one of these shafts is usually positively driven and the other driven in turn therefrom.

It will be understood that a fibrous strand is fed forward between each set of drawing rolls by the rotation thereof and that the scavenger roll is placed beneath the drawing rolls so that if the strand breaks, it will be caught by, and wound upon, the scavenger roll so as not to become entangled in the machine. When this happens, the operator pieces the broken strand to continue the operation and removes from the scavenger roll the portion of the strand which has been wound thereon.

The yarn forming frames often extend a great

2

er length with the sets of cooperating drawing rolls at spaced intervals throughout the length of the frame. Since the construction is the same throughout, it is only necessary to illustrate and refer to but two sets of such drawing rolls. Heretofore a stub shaft with a frusto-conical scavenger roll at each end thereof has been associated with each two sets of the drawing rolls but a special driving shaft has been provided for operating these series of independent scavenger roll stub shafts thus requiring bearings for this shaft throughout the machine, a drive therefor, and no means for ready removal and replacement of the scavenger roll shafts and their supports.

15 In the drawings:

Fig. 1 is a front elevation of such portion of a yarn forming frame, more particularly a spinning frame, as is sufficient for a disclosure of the present invention,

20 Fig. 2 is a view generally in side elevation and partially in cross section on the line 2—2, Fig. 1, with some additional portions of the frame included.

25 In the construction illustrated each set of drawing rolls is shown as comprising an upper fluted roll 10, a cooperating lower fluted roll 11, and a pressure roll 12, the latter roll being removed in Fig. 1. These sets extend in horizontal alignment throughout the length of the frame. In the 30 particular construction illustrated, the lower rolls 11 are all mounted upon, or formed from part of, a common horizontal shaft 13 and similarly the upper rolls 10 are all mounted upon, or form part of, another horizontal shaft 14 extending in parallelism with the shaft 13. In this construction both of these shafts 13 and 14 are driven. The lower shaft 13 having a beveled gear 15 driven from any suitable driving connection in the frame, and the upper shaft 14 being driven from the lower shaft by means of the sprocket chain 16 engaging sprocket wheels on their respective 35 shafts.

40 The yarn strand in the usual manner is fed forwardly between the cooperating rolls 10 and 11 and beneath the pressure roll 12, when employed, to any of the usual mechanisms employed in twisting, spinning, or otherwise forming yarn in a manner well known to those skilled in the art.

45 There is provided with each two adjacent sets 50 of the cooperating rolls, such as illustrated in Fig. 1, a stub shaft 17 having free ends and on each of these free ends is mounted a frusto-conical scavenger roll 18 with the larger end toward the center and the small end toward the free end 55 of the shaft. This roll as usual may be covered

with felt or other material readily to catch a broken strand. With this type of scavenger roll the strand may be collected thereon and may be readily removed by pulling it off over the small end of the roll.

The drive for each stub shaft 17 is taken directly from a common horizontally driven shaft of the aligned drawing rolls and, in the case illustrated, from the lower driven shaft. For this purpose a pulley 19 is mounted on the stub shaft centrally thereof and between the larger ends of the scavenger rolls, and a belt 20 extends around this pulley and the shaft 13 between the sets of the drawing rolls. The stub shaft 17 is supported in a bearing bracket having arms 21 presenting at their upper ends bearings for the stub shaft at opposite sides of the pulley 19. This bearing bracket is provided with a pivot 22 shown as a short shaft connecting the arms 21 at their lower ends and this pivot is journaled in a support 23 mounted on a suitable portion 24 of the frame. These parts are also positioned as to present the two scavenger rolls respectively beneath adjacent sets of drawing rolls such as the two sets illustrated.

Each bearing bracket is extended rearwardly from its pivot at 25, and this extension is connected by a suitable spring 26 to some fixed portion 27 of the frame so that there is a spring between the bearing bracket and the frame which acts to maintain tension on the belt and thus insure that each stub shaft with its scavenger rolls shall be independently and positively driven from the shaft 13.

The bearings for the stub shaft in the arms 21 of the bearing bracket are as shown open bearings and faced downwardly. Thus by releasing the tension of the spring, the bearing bracket may be swung counter-clockwise on the support 23 thus enabling the stub shaft with the scavenger rolls entirely to be removed from the bearings, slipped out through the belt and repaired or renewed or replaced.

The bearing on the support 23 for the pivot 22 of the bearing bracket also as shown, is open and faces downward so that when the spring 26 is released, the entire bearing bracket with the stub shaft and scavenger rolls may be readily removed from the frame and repaired or renewed or replaced.

There is thus presented a very simple and efficient mechanism by means of which each pair of scavenger rolls is independently driven directly from a driven shaft common to the associated sets of drawing rolls thus requiring no additional driving shaft or mechanism than that required for driving the drawing rolls themselves, and furthermore each stub shaft with its scavenger rolls and each bearing bracket therefor are independently readily removed and replaced whenever desired.

Having thus described the invention, what is

claimed as new, and desired to be secured by Letters Patent, is:

1. In a yarn forming frame provided at spaced intervals with sets of horizontally aligned co-operating drawing rolls including a common horizontal driven shaft therefor the combination of a stub shaft having free ends, a frusto-conical scavenger roll mounted on each end of the stub shaft, a pulley mounted on the stub shaft centrally thereof and between the larger ends of the scavenger rolls, a bearing bracket having bearings for the stub shaft at opposite sides of the pulley and pivotally mounted on the frame beneath and parallel to the drawing rolls to position the scavenger rolls respectively beneath adjacent sets of drawing rolls, a belt extending around the pulley and the driven drawing roll shaft between said adjacent sets of drawing rolls, and a spring between the bearing bracket and the frame acting to tension the belt.
2. In a yarn forming frame having the combination defined in claim 1, in which the said bearings for the stub shaft are open and downwardly facing to enable the stub shaft, upon relaxation of the spring, readily to be removed and replaced.
3. In a yarn forming frame having the combination defined in claim 2, in which the frame beneath the bearing bracket is provided with a support having a downwardly facing open bearing and in which the bearing bracket is pivotally mounted on the frame by means of a shaft secured in the bracket and mounted in the open bearing of the support thus to enable, upon disconnection of the spring, the bearing bracket readily to be removed and replaced.
4. In a yarn forming frame provided at spaced intervals with sets of horizontally aligned co-operating drawing rolls including a common horizontal driven shaft therefor the combination of a stub shaft having free ends, a frusto-conical scavenger roll mounted on each end of the stub shaft, a belt extending around the central portion of the stub shaft and the driven drawing roll shaft between said adjacent sets of drawing rolls, a bearing bracket having bearings for the stub shaft at opposite sides of the belt and between the belt and the larger ends of the scavenger rolls and pivotally mounted on the frame beneath and parallel to the drawing rolls to position the scavenger rolls respectively beneath adjacent sets of drawing rolls, and a spring between the bearing bracket and the frame acting to tension the belt.
5. In a yarn forming frame having the combination defined in claim 4, in which the said bearings for the stub shaft are open and downwardly facing to enable the stub shaft, upon relaxation of the spring, readily to be removed and replaced.
